HANDLE AND SEPARATOR SECTION FOR A CARRIER FOR BOTTLES OR THE LIKE

William J. Hrozenchik, Norwalk, Conn., assignor to Diamond International Corporation, New York, N.Y., a corporation of Delaware

Filed May 10, 1966, Ser. No. 2,242

Term of patent 14 years

(Cl. D58—26)

FIG. 1.

FIG. 2.

FIG. 3.

FIG. 4.

FIG. 5.

FIG. 6.

FIG. 7.

FIG. 1 is a perspective view of a handle and separator section for a carrier for bottles or the like showing my new design;

FIG. 2 is a top plan view thereof on an enlarged scale;

FIG. 3 is a side elevational view thereof as seen from the front of the perspective view of FIG. 1;

FIG. 4 is an end elevational view seen from the right side of the perspective view of FIG. 1;

FIG. 5 is a fragmentary elevational view of the handle portion seen from the rear of the side elevational view of FIG. 3;

FIG. 6 is a fragmentary cross section on line 6-6 of FIG. 2; and

FIG. 7 is a sectional view on line 7-7 of FIG. 2.

I claim:

The ornamental design for a handle and separator section for a carrier for bottles or the like, as shown.
